UNITED STATES PATENT OFFICE.

FRANK R. LUECK, OF MILWAUKEE, WISCONSIN.

GRINDER ATTACHMENT FOR DRILLS.

1,426,579.

Specification of Letters Patent. Patented Aug. 22, 1922.

Application filed August 2, 1920. Serial No. 400,694.

To all whom it may concern:

Be it known that I, FRANK R. LUECK, a citizen of the United States, residing at Milwaukee, in the county of Milwaukee and State of Wisconsin, have invented certain new and useful Improvements in Grinder Attachments for Drills, of which the following is a specification, reference being had to the accompanying drawing, forming 10 a part thereof.

The main objects of this invention are to facilitate accurately and symmetrically grinding and sharpening drills of different sizes to predetermined cutting and clearance angles; 15 to provide for easy and quick removal of the drill holder from the grinder for convenient inspection of the work and for its adjustment in the holder without disturbing the adjustments of the work and parts of the attachment relative to one another and to the grinding wheel; to facilitate clamping drills of different sizes in proper grinding position in the drill holder; and generally to improve the construction and operation of 20 devices of this class.

It consists in the construction, arrangement and combination of parts as hereinafter particularly described and pointed out in the claims.

30 In the accompanying drawing like characters designate the same parts in the several figures.

Figure 1 is a plan view of a grinder attachment for drills embodying the invention 35 as applied to a grinder of typical construction, parts of which are shown; Fig. 2 is a vertical section on the line 2-2, Fig. 1, showing the adjustable connection between the drill holder and its support for advancing the holder towards the working face of the grinding wheel and grinding both lips of the drill alike; Fig. 3 is a side elevation of a portion of the attachment as viewed from the right relative to Fig. 1, the annular bracket or support being shown in cross section; Fig. 4 is an end elevation of the drill holder removed from the rest of the attachment and as viewed towards the point of a drill held therein; Fig. 5 is an inverted 40 perspective view of the end of the drill holder nearest the grinding wheel; and Fig. 50 5 is a section on the line 6-6, Fig. 1, of the swivel joint connection between the drill holder and its support.

55 The attachment consists of an oscillatory drill holder comprising an angle or V-shaped

bar 1, which is connected at an oblique angle thereto by a swivel joint with a channeled head 2, mounted on an angular bracket or support 3. The bracket or support 3 is adjustably mounted on an arm 4, which is fastened by a screw 5 to the case or frame 6 of a grinder. The screw 5 is arranged parallel with the axis of the grinding wheel 8, and the arm 4 is angularly adjustable on 60 the screw for raising or lowering the drill holder and its support relative to the grinding wheel. The bracket or support 3 is formed at one end with a collar or sleeve 10, which is slidably fitted on and adjustable 65 lengthwise of the arm 4. From the collar 10 the bracket extends transversely to the arm 4 in front and below the center of the grinding wheel 8 and thence upwardly, terminating at the end opposite the collar with 70 a cylindrical socket or guideway 11, parallel with the collar 10 and at right angles or transverse to the axis of the grinding wheel. The bracket 3 is fastened in adjusted position on the arm 4 by a thumb screw 12. 75

The head 2 is provided at an oblique angle thereto with a hollow cylindrical shank 14, which is fitted and adjustable lengthwise in the socket 11, being held against turning therein by a spline 15, as shown in Fig. 2. 80

A rod 17 fastened at one end in the head 2 and extending axially through the shank 14 and a hole in the opposite end of the socket 11, is threaded and provided at the end protruding from the socket with a graduated adjusting nut 18. A spring 20 inserted in the hollow shank 14 and bearing at one end against the head 2 and at the opposite end against the closed end of the socket 11, tends to shift the head with the 85 drill holder carried thereby, away from the grinding wheel, and holds the hub of the nut 18 in engagement with the socket 11. An index or pointer 21, attached to the socket 11 and projecting over the graduated periphery of the nut 18, indicates the position of the drill holder relative to the working face of the grinding wheel, and enables the operator to determine with accuracy the extent to which a drill is advanced by the nut 90 100 105 110 towards the grinding wheel, so that both lips of the drill may be ground exactly alike.

The swivel joint connection between the drill holder and its support by which the proper movement of the holder is determined for grinding drills with cutting edges at the proper angle and with proper clear-

ance, comprises a swivel block 23, fitted in the channel of the head 2 and pivoted therein adjacent its outer end on a pin 24, and a swivel pin 25, rotatably and removably fitted in the block 23 and adjustably attached to the drill holder. The head 2 is provided with a pin or key 27, projecting into the channel opposite the open side thereof, and the swivel pin 25 is formed 10 with a circumferential groove 28 arranged to engage with the pin or key when the parts of the attachment are assembled in working position, the swivel block being cut away or recessed to receive the pin or key and 15 permit engagement therewith of the groove in the swivel pin, as shown in Fig. 1.

The swivel block 23 is automatically locked and releasably held in place in working position in the channel of the head 2 20 by a spring pin or latch 30, as shown in Fig. 6, the block being beveled on the back side to lift the pin and permit it to drop into engagement with a socket in the block when the block is swung on its pivot pin 24 into 25 place in the channel of the head 2.

The swivel pin 25 is provided at its inner end with a head 32 having a tongue and groove sliding and guiding connection with a head 33, attached to the inner end of the 30 drill holder 1. The head 33 of the drill holder is fastened in adjusted position to the head 32 of the swivel pin by a thumb screw 34 passing through a longitudinal slot in the head 32 and threaded in the head 33. 35 The tongue and groove sliding connection between the heads 32 and 33 and the slot in the head 32 are substantially parallel with the plane of rotation of the grinding wheel 8 and also with the shank 14 of the head 2 40 and the arm 4.

As shown in Fig. 5, the head 33 is provided on one edge with a scale 36, and the head 32 has an index edge 37 overhanging the scale, to adjust the holder for grinding 45 drills of different sizes.

The swivel block 23 and the head 32 are formed with stop lugs 39 and 40, for limiting the upward movement of the outer end of the drill holder and determining the proper 50 initial position of the holder for grinding the lips of drills. For properly positioning and securing drills of different sizes in the V-shaped bar of the holder, the holder is provided with an adjustable clamp and with an 55 adjustable stop.

The clamp consists of an elongated jaw 42, which is pivotally connected with a yoke or loop 43 slidably mounted and adjustable lengthwise of an arm 44 extending from the 60 head 33 transversely over the angle bar 1. A thumb screw 45 threaded in an extension or outwardly projecting arm 46 of the jaw and arranged to engage with the under side of the arm 44, simultaneously clamps 65 the yoke or loop 43 in place on the arm 44

and forces the jaw 42 into engagement with the side of a drill in the angle bar 1, securely holding it in place therein.

Separation of the yoke 43 to which the jaw 42 is pivoted, from the arm 44, is prevented 70 by a stop pin 47 inserted in and projecting from the arm adjacent its outer end.

The adjustable stop for preventing end-wise displacement of drills in the angle bar 1, consists of a block 49 formed with an 75 angular opening corresponding with the bar 1, on which it is slidably mounted and secured in adjusted position by a thumb screw 50. The block 49 is provided with an outwardly extending arm 51 fitting into the 80 angle of the bar 1 and supporting the block in a plane perpendicular to the wings of the angle bar.

A gage plate 53, attached to the inner end of the head 33 and overhanging the upper 85 wing of the angle bar 1, by engagement with the leading spiral edges of a drill, determines the proper position of the lips of the drill for grinding.

The extended axis of the swivel pin 25 in 90 its normal working position, as shown in Fig. 1, crosses the longitudinal center of the angle bar 1, and the axis of a drill held therein a short distance above and at an oblique angle thereto, and provides for the 95 required clearance in grinding the lips of drills of different sizes.

In the operation of the attachment for grinding a drill of any given size, the head 33 of the angle bar 1 is adjusted for that 100 size with relation to the head 32 by means of the scale 36 and index edge 37, and fastened relative to the head 32 and swivel pin 23 by the screw 34.

The drill being placed in position in the 105 angle bar 1 with one of its leading spiral edges in engagement with the overhanging gage plate 53, and its angular cutting edge projecting a sufficient distance in advance of said plate for grinding, the yoke or loop 110 43 is adjusted on the arm 44 to proper position, the jaw 42 is forced by the screw 45 against the side of the drill, thereby clamping it firmly in place against the wings of the angle bar 1, and the stop block 49 is 115 adjusted to bear against the outer end of the drill shank and secured in place by the screw 50. The nut 18 being turned clockwise on the threaded rod 17 to a position which will permit of a sufficient advance 120 movement of the drill holder relative to the bracket or support 3, for grinding the drill, and the arm 4 and bracket or support 3 being adjusted so that the lip or edge of the drill to be ground will 125 be presented to the periphery of the grinding wheel 8 horizontally opposite its center when the drill holder is in its initial working position, as shown by full lines in Figs. 1 and 3, the holder is advanced by turning the 130

nut 18 counterclockwise till the lip or edge of the drill is brought into contact with the wheel, and the wheel being rotated, the holder with the drill is rocked by the operator, as indicated in Fig. 3, downward and upward from and to its initial position, determined by the stop lugs 39 and 40, the nut 18 being turned further counterclockwise if necessary to advance the drill towards the wheel, and the foregoing operations repeated till a sharp and true cutting edge is obtained.

The adjustment of the nut 18 at the limit of the advance movement of the drill holder, as indicated by the index 21, being noted, the pin 30 is withdrawn from engagement with the swivel block 23 and the drill holder is swung on the pivot pin 24 away from the grinding wheel, as indicated by dotted lines in Fig. 1. The clamp 42 is then released and the drill is turned into a clamping position for grinding the other lip. The nut 18 being turned counterclockwise to allow for the required advance movement of the holder, the holder is swung back into and automatically locked by the spring pin 30 in operative position. The holder with the drill is then advanced towards the grinding wheel by the nut 18 and rocked on its swivel connection with the head 2 till the second lip is ground at exactly the same angle and with the same clearance as the first lip, the nut 18 being turned counterclockwise in advancing the drill to exactly the same point, as determined by the index 21, as before, for grinding the first lip.

When the drill holder is swung with the swivel block 23, away from the grinding wheel, as indicated by dotted lines in Fig. 1, it is released and can be withdrawn from the swivel block for more conveniently resetting, replacing or inspecting a drill.

The removal of the drill holder and the angle bar 1 from the swivel block 23 does not change or affect any of the adjustments of the attachment. For grinding drills of larger diameters or sizes, the head 33 with the angle bar 1, is set forward toward the grinding wheel 8 with relation to the swivel pin head 32 according to the scale 36, so that the lips of the larger drills will be ground to a longer radius, the extended axis of the swivel pin 25 crossing the axis of the drill further from the grinding face of the wheel.

Various changes in the details of construction and arrangement of parts may be made without departure from the principle and scope of the invention as defined in the following claims.

I claim:

1. In a grinder attachment for drills the combination of a support connected with the grinder frame, a drill holder, a swivel joint normally connecting the drill holder

with said support at an oblique angle to said holder and to the working face of the grinding wheel and comprising members separably fitted to each other, one of the swivel members being pivotally connected transversely to its axis with said support to permit the drill holder to be swung into and out of operative position relative to the grinding wheel, means for locking the pivoted swivel member to said support in operative position, and means adapted to automatically lock the swivel members together in normal working relation to each other when the pivoted swivel member is swung into operative position and to unlock said members and permit the removal of the drill holder when said pivoted swivel member is swung out of operative position.

2. In a grinder attachment for drills the combination of a support connected with the grinding frame, a drill holder having an oscillatory separable connection with said support on an axis disposed at an oblique angle to the holder and normally at an oblique angle to the axis of the grinding wheel and having a pivot connection with the support on an axis which is transverse to the axis of oscillation and on which the holder is adapted to be swung towards and from the grinding wheel into and out of operative position, means for automatically locking and releasing said oscillatory connection when the holder is swung into and out of operative position, and means for locking the holder in operative position.

3. In a grinder attachment for drills the combination of a support connected with the grinder frame, a drill holder, a swivel block, a swivel pin fitted to turn in said block, one of the swivel members being pivotally connected transversely to its axis with said support and adapted to be swung into and out of normal position at an oblique angle to the working face of the grinding wheel and the drill holder being attached to the other swivel member at an oblique angle thereto and to the plane of the grinding wheel, means for fastening the pivoted swivel member in normal position to said support, and means for automatically fastening the swivel members together when they are swung into normal position and for releasing them to permit the removal of the drill holder when they are swung out of normal position.

4. In a grinder attachment for drills the combination of a head connected with the grinder frame at an oblique angle to the working face of the grinding wheel and provided with a key, a drill holder, a swivel block, a swivel pin fitted in said block, one of the swivel members being pivotally connected transversely to its axis with said head and the other swivel member being attached to the drill holder at an oblique angle

thereto and normally to the working face of the grinding wheel and provided with a circumferential groove for engagement with said key when the parts are in operative position, and a spring latch for releasably locking one swivel member to said head in working position.

5. In a grinder attachment for drills the combination of a support connected with

- 10 the grinder frame and having a guide-way parallel with the plane of the grinding wheel, a head having a shank fitted and longitudinally adjustable in said guide-way, a spring tending to shift said head away from
- 15 the grinding wheel, a screw and graduated nut adjustably connecting the head with said support for determinately shifting said head towards the grinding wheel, and a drill holder connected with said head
- 20 obliquely to the plane of the grinding wheel by a swivel joint at an oblique angle to the holder and to the working face of the grinding wheel.

6. In a grinder attachment for drills the combination of a support adapted for attachment to the grinder frame, a head having an adjustable graduated screw connection with said support and movable parallel with the plane of the grinding wheel towards and from its axis, a drill holder connected with said head by a swivel joint comprising two separable members normally disposed obliquely to the peripheral working face of the grinding wheel

- 30 and to the holder and movable into abnormal position to permit the removal of the holder, the holder being connected with one swivel member by a graduated sliding joint and adjustable parallel with the plane of
- 35 the grinding wheel towards and from its working face, and means for releasably fastening the swivel members together in normal working position.

7. In a grinder attachment for drills the combination of a support, a channeled head provided in its channel with a key and having a shank disposed obliquely to the channel and adjustable longitudinally in said support, a swivel block fitted and pivoted transversely to its axis in the channeled head and recessed to receive said key, a swivel pin fitted in the swivel block and circumferentially grooved to engage with said key to confine the pin in the swivel block when it is turned on its pivot into working position in the channeled head,

a drill holder attached to the swivel pin at an oblique angle thereto, and means for reasonably locking the swivel block in its normal position in the channeled head.

8. In a grinder attachment for drills the combination of a support provided with a channeled head disposed obliquely to the working face of the grinding wheel and provided in its channel with a key, a swivel block fitted and pivoted transversely to its axis in the channeled head and transversely recessed to receive the key, a swivel pin removably fitted in the swivel block and formed with a groove to engage with the key in the channeled head when the swivel block is in working position, means for releasably locking the swivel block in working position in the channeled head, and a drill holder having a graduated adjustable slide connection with the swivel pin at an oblique angle thereto.

9. In a grinder attachment for drills the combination of a support, a channeled head provided in its channel with a key and having a shank disposed obliquely to the channel and adjustable longitudinally in said support, a swivel block pivoted transversely to its axis in the channeled head into and out of working position in which it is adapted to be turned on its pivot, a drill holder having an adjustable slide connection with the swivel pin at an oblique angle thereto, and means for automatically and releasably locking the swivel block in working position in the channeled head.

10. In a grinder attachment for drills the combination of a support connected with the grinder frame, a drill holder of V-shaped cross section connected obliquely to the plane of the grinding wheel with said support by a swivel joint having its axis at an oblique angle to the length of the holder and to the plane of the grinding wheel, and an adjustable clamp comprising an arm attached to and extending transversely from the holder, a loop slidably mounted on the arm, a jaw pivotally connected with the loop, and a screw threaded in an extension of the jaw and adapted by engagement with the arm to force the jaw into engagement with a drill in the holder between its wings.

In witness whereof I hereto affix my signature.

FRANK R. LUECK.
